METHOD FOR COOLING AND LUBRICATING CUTTING TOOLS

Ernest G. White, Cleveland, Ohio, assignor to The Standard Oil Company, Cleveland, Ohio, a corporation of Ohio

Application October 24, 1952, Serial No. 316,754

1 Claim. (Cl. 29—106)

The present invention relates to cutting methods and apparatus and, more particularly, to improvements in cooling of cutting tools and chip lubrication.

In the cutting of metals, such as on a lathe, planer, threader, etc., it has long been appreciated that the use of a cutting fluid has the effect of improving the smoothness of the cut surface and of increasing tool life. Many proposals have been made with respect to the manner in which such a cutting operation can be improved, but most of these involve cooling the tool and the work surface and lubricating the relatively moving parts. All of these involve some method of applying the cutting fluid to the cutting site.

The most common method is to permit a stream of fluid to flow over the tool and the work. Other proposals direct a stream of the fluid under pressure from various directions. All of these methods are more or less deficient in achieving satisfactory cooling and lubricating in the space between the tool and the work, where adequate lubrication is the most essential.

Accordingly, it is a primary object of the present invention to force a cutting liquid to penetrate more effectively to the cutting edge of a tool.

In accordance with the invention a continuously replenished volume of cutting liquid at a moderate hydrostatic pressure is subjected to ultrasonic longitudinal vibrations which establish high dynamic pressures in a jet issuing from a chamber. The dynamic pressures force the jet into intimate contact with the tool close to the cutting edge thereof.

In order that this invention may be more fully understood, it will now be described with reference to the accompanying drawing wherein the single figure is a schematic diagram of an embodiment of the invention.

Referring now to the drawing, a rotatable workpiece 11 is shown against which a cutting tool 12 is held by a tool holder 13, which is arranged by a conventional mechanism (not shown) to be moved toward and away from the workpiece 11 and to be translated parallel to the axis of rotation thereof. A chamber 14, adapted to contain cutting liquid, is secured by an adjustable bracket 15 to the tool holder 13 generally beneath the tool 12 and on the side facing the wedge-shaped opening 16 formed between the tool and the work and having the cutting edge 17 as an apex. The chamber 14 may be slid toward or away from the opening 16 and fixed at the most effective distance by a thumbscrew 20. The transverse position of the chamber 14 may be varied within limits by means of appropriate slots 32 in the bracket 15 and their associated wing nuts 33. Further mechanical adjustments may be provided for if desired.

The chamber 14 in the illustrated form of the invention comprises a hollow cylindrical tube 18 having an upper cover plate 19 and a base assembly 21, secured thereto and substantially enclosing the same with the exception of an aperture 22, which may be provided with one or more nozzles 23 located substantially in the center

2

of the upper cover plate 19. The chamber 14 is connected through a flexible tube 24 to a liquid pump 25 which draws cutting liquid from a sump 26 beneath the workpiece 11 and supplies the same under pressure to the chamber 14 to maintain the same filled with liquid.

As a result a stream 27 of cutting liquid emerges from the nozzle 23 and is directed into the wedge-shaped opening 16. The stream 27 may comprise a sheet of liquid parallel to the cutting edge 17 or it may be composed of a plurality of spaced parallel jets. The pressure of the liquid supplied by the pump 25 need only be such as will direct the stream 27 to the tool. The pressure is not critical but systems operating on low pressure, such as about 50 pounds per square inch and under, are more economical to construct and are preferred.

In accordance with a theory advanced to explain the effect of cutting liquids in increasing tool life, the cutting liquid is vaporized as a result of the high temperature adjacent the cutting edge. The heat required for vaporization substantially cools the cutting edge and the vapor passes through minute spaces caused by relative vibration between the tool and the workpiece or by slight irregularities in both the cutting edge and the work surface. The vapor then condenses on the top of the tool underneath the chip 28 that comes from the workpiece in an area where the cutting liquid is most effective in reducing the frictional resistance to the movement of the chip.

The apparatus of the present invention is adapted to obtain intimate contact between the stream of cutting liquid by the extremely high pressures inherent in ultrasonic longitudinal vibrations which are superimposed upon the stream 27. For this purpose a transducer of longitudinal vibrations is associated with the chamber 14.

The transducer may take the form of an X-cut piezoelectric crystal 29 which is supported by an electrically insulating holder 30 forming a portion of the base assembly 21. Both faces of the crystal 29 are conductively coated, the front face being in contact with the liquid in the chamber 14 and the rear face being supported by the holder 30 which resists the hydrostatic pressure. The front coating is electrically connected to the tube 18 which is maintained at ground potential to avoid shock hazard. The rear coating of the crystal 29 is connected to an oscillator 31 adapted to generate ultrasonic electrical waves, which excite corresponding mechanical vibrations in the crystal.

Preferably the distance from the face of the crystal 29 to the inner surface of the cover plate 19 is so related to the wave length of the vibrations in the cutting liquid that the reflections from the plate 19 are additive to the motion of the crystal. Under this condition, the above-mentioned distance is some whole number of half wave lengths, and the energy transmitted into the cutting liquid is maximum.

It is also desirable to concentrate the energy in the direction of the aperture 22 and to avoid as much as possible reflections from the side of the tube 18. In the usual crystal, the energy is radiated in a beam having a solid angle that is directly proportional to the wave length and inversely proportional to the transverse dimension of the crystal. Accordingly, a high frequency and a large crystal face are seen to be favorable. A crystal having a concave face may be employed to focus the vibrations on the aperture 22.

The hydrostatic head tends to dampen the crystal vibrations; consequently the lowest static pressure that still provides an accurately dirigible stream 27 is most advantageous.

When ultrasonic waves are projected against a boundary, which in this case is the apex of the wedge-shaped opening 16, an alternating pressure is produced at the

frequency of the wave propagation. This alternating pressure is directly proportional to the product of the acoustic impedance of the vibrating medium, the frequency of vibration, and the square of the amplitude of the vibrating particles. The acoustic impedance is proportional to the product of the density of the medium and the velocity with which vibrations are transmitted through the medium. Since the cutting liquid is chosen primarily on the basis of its cooling and lubricating properties, little control is had over the acoustic impedance. However, a high frequency may be selected to provide high pressures. Also, since the square of the amplitude is proportional to the radiated power, the power of the oscillator 31 is preferably substantial. Although the alternating motion of the liquid is extremely small, the alternating pressures may readily be made extremely large.

The cutting liquid is thus forced by the ultrasonic alternating pressure present in the stream 27 into intimate contact with the tool 12 close to the cutting edge 17 thereof and through the extremely small clearance between the tool and the workpiece to permit lubrication of the tool-chip interface.

It is to be pointed out that according to the findings of the prior art, if the speed of the stream is greater than a certain value, the boiling action at the apex of the wedge-shaped opening 16 is reduced and the heat transference and lubrication are impaired. Apparently this effect is a result of an excessive quantity of cutting liquid in the opening 16. On the other hand, a high stream speed has heretofore been proposed as one way of achieving the necessary penetration to the vicinity of the cutting edge. These conflicting criteria are made substantially compatible by employing ultrasonic alternating pressure superimposed upon the moving stream 27 in accordance with the present invention.

It is to be understood that an overhead coolant spray may be provided to catch the stream of cutting liquid when the tool is not engaged with the workpiece and to absorb the smoke and vapor generated by the cutting oper-

ation. Likewise a chip guard may be employed to prevent the chip from intercepting the stream.

While I have described my invention in a preferred embodiment employing a crystal as the source of ultrasonic energy, other means for this purpose known in the art, such as a magnetostrictor, may be employed.

Although the invention has been disclosed with reference to a simple lathe type of cutting operation, it will be appreciated that it is applicable to many other types of machine operations such as, for example, milling wherein the workpiece is stationary and the tool moves relative thereto.

I claim:

A method of cooling and lubricating cutting tools comprising the steps of directing a stream of cutting liquid at a pressure of not over 50 pounds per square inch into the wedge-shaped space formed by a workpiece and the relief angle of a cutting tool so that the stream impinges substantially on the cutting edge of said tool along the line of its contact with the workpiece, and inducing ultrasonic longitudinal vibrations within said stream.
